(57) **CLAIM**

The ornamental design for a double electric pump design, substantially as shown and described.

DESCRIPTION

FIG. 1 is a front view of a double electric pump design of the present invention;

FIG. 2 is a rear view of the invention illustrated in FIG. 1; FIG. 3 is a left-side view of the invention illustrated in FIG. 1;

FIG. 4 is a right-side view of the invention illustrated in FIG. 1;

FIG. 5 is a top view of the invention illustrated in FIG. 1; FIG. 6 is a bottom view of the invention illustrated in FIG. 1;

FIG. 7 is a front perspective view of the invention of FIG. 1;

FIG. 8 is a rear perspective view of the invention of FIG. 1; and,

FIG. 9 is a side perspective view of the invention of FIG. 1. The broken lines in the drawings illustrate portions of the double electric pump design or accessories thereto and form no part of the claimed design.

1 Claim, 9 Drawing Sheets
